J. E. SIMPSON & C. J. PAULSON.
ATTACHMENT FOR CHECK WRITING MACHINES.
APPLICATION FILED MAR. 13, 1916.

1,241,570.

Patented Oct. 2, 1917.

UNITED STATES PATENT OFFICE.

JAMES E. SIMPSON AND CHARLES J. PAULSON, OF BROOKLYN, NEW YORK. ASSIGNEES
TO TODD PROTECTOGRAPH COMPANY, OF ROCHESTER, NEW YORK, A CORPORATION
OF NEW YORK.

ATTACHMENT FOR CHECK-WRITING MACHINES.

1,241,570.

Specification of Letters Patent.

Patented Oct. 2, 1917.

Application filed March 13, 1916. Serial No. 83,949.

To all whom it may concern:
Be it known that we, JAMES E. SIMPSON and CHARLES J. PAULSON, both of Brooklyn, county of Kings, and State of New York, 5 have invented certain new and useful Improvements in Attachments for Check-Writing Machines; and we do hereby declare the following to be a full, clear, and exact description of the same, such as will 10 enable any person skilled in the art to which the invention appertains to make and use the same.

This invention relates to printing or marking apparatus of the variety known as 15 "check protectors" or "check writers," and more particularly to machines of this variety in which the printing couple is constructed to emboss or disrupt the paper printed upon in order that it may absorb 20 the printing ink and thus render alteration of the inscription practically impossible.

In the use of machines of this kind it is sometimes attempted to "raise" a check upon which an amount has already been 25 printed, by replacing it in the machine and printing a second inscription for a larger amount over the amount previously written. It is the object of this invention to provide these machines with a device which 30 does not interfere with the printing of an amount upon fresh, unbroken paper, but which operates to prevent a second impression by the machine on any check upon which an impression has previously been 35 made, thus rendering it practically impossible to alter a check in this manner. To this end the invention provides a means acting upon the paper in the region of the printing line to engage and tear any portion 40 of it of which the fibers have been embossed or disrupted by a previous impression.

Other objects and advantages will appear in connection with the following detailed description of one embodiment of the invention illustrated in the accompanying drawings in which:—

Figure 1 is a top plan view, partly broken away, of the check writing machine in which the invention is embodied.

Fig. 2 is a central, longitudinal section of the same in elevation.

Fig. 3 is a transverse, sectional elevation

taken substantially on the line 3—3 of Fig. 2.

Fig. 4 is an enlarged top plan view of a portion of the paper mutilating device.

Fig. 5 is a sectional elevation, enlarged, of a portion of the paper mutilating device and the platen, taken substantially on the line 5—5 of Fig. 4.

Fig. 6 is a fragmentary elevation, enlarged, of the paper mutilating points as viewed from the left side of the machine in Figs. 3 and 5.

In check writing machines of a variety in common use, the printing surfaces of the type and platen are formed so as to emboss, or disrupt, the fibers of the paper during the printing impression to permit the paper to more readily absorb the ink and thus to increase the difficulty of alteration. It has at times been attempted to "raise" a check printed by these machines by partially removing the ink of the first impression, reinserting the check in the machine, and superimposing a second impression upon the first one calling for the payment of a larger amount than the check was originally intended to convey. The present invention is designed to provide a device for check writing machines which will mutilate a check which has once received an impression, or otherwise obstruct a printing operation thereon when reinserted in the machine for the purpose of printing it a second time.

This invention is capable of adaptation to any check writing machines of the variety described, and in its present embodiment is shown in combination with a machine substantially of the type disclosed in U. S. Letters Patent No. 1,138,330 granted May 4, 1915, to Todd and Tiefel, and a brief explanation will be sufficient for an understanding of the construction and operation of this machine. Referring to Figs. 1, 2 and 3, the machine comprises a supporting and inclosing frame having a base portion 1 and an upper portion 2, separated throughout most of their extent by a check receiving slot 3 above a printing bed 3^a on the base portion of the frame. Journaled at its ends in the ends of the upper portion 2 of the frame is the main shaft 4 of the machine, supporting a yoke 5 which is longitudinally

slidable on the shaft but is held against rotation therewith by means of guide rails 6 on the frame and a coöperating roller 7 mounted on the yoke. The latter is provided with a handle 8 extending without the casing 2, by which the yoke may be shifted longitudinally on the shaft 4.

The yoke 5 encl. faces a cylindrical type carrier 9 rotatably mounted on the bearings 10 of the yoke so that the carrier may be shifted longitudinally of the shaft 4 by means of the sliding movement of the yoke, but the carrier is provided with a key (not shown) engaging in a keyway 11 in the shaft 4 so that the carrier is rotated by the rotation of shaft 4. The means for rotating the shaft comprises a gear 12 fixed to the shaft and having a geared connection with the operating crank 13 on the exterior of the casing.

The type carrier is provided on its periphery with a plurality of type forms 14 spaced from each other longitudinally of the carrier and extending in parallel relation circumferentially thereof. The handle 8 carries a pointer 15 moving over a dial 16 bearing characters corresponding to the types on the carrier, so that when the pointer 15 is moved into registry with one of the characters on the dial 16 by means of the handle 8, the type carrier is shifted longitudinally to bring the corresponding type form to a common printing position near the center of the machine.

The means for pressing the paper into printing engagement with the types comprises a rotary platen wheel 17 fixed on a spindle 18 journaled at its ends in a forked arm 19 adjustably attached to a shaft 20 extending longitudinally of the machine. Arm 19 carries an extension 21 adjacent an arm 22 fixed on the shaft 20, and adjusting screws 23 of a common variety are provided between the extension 21 and arm 22 for adjusting the position of the platen relative to the shaft 20. The shaft 20 is provided at its other end with an upwardly extending arm 24 (Fig. 3) arranged to engage at its upper end with a cam 25 (Fig. 2) adjacent the end of the shaft 4. It will now be understood that when the carrier has been shifted longitudinally to bring one of its type forms to printing position opposite the platen, and the crank 13 is revolved, the carrier will be rotated to move the selected type form toward the platen wheel 17. As the type form approaches the platen the latter is raised into position to coöperate in rolling engagement with the type form through a rocking motion of the shaft 20 imparted by means of the cam 25 and arm 24. After the impression, cam 25 permits the platen to be lowered to inactive position substantially level with the printing bed by means of a spring 25a. Thus the rolling co-

operation of a type form with the platen serves to simultaneously print the paper and feed it across the printing bed. The surfaces of the type forms and platen are provided with coöperating projections, one form of which, as shown in the illustration of the platen in Figs. 2 and 4, comprises ribs or corrugations extending circumferentially of the platen and the type carrier, but it will be understood, of course, that these projections may be formed in a variety of ways. These projections on the types and platen are arranged to register or intermesh with each other so as to break the surface of the paper during the printing impression, as fully explained in Patent No. 1138330 referred to above.

The means for guiding the paper during its feeding movement comprises a small roller 26 journaled on the printing bed 85 (Fig. 3), upon which is arranged to bear a resilient finger 27 fixed to a bracket 28 on the casing. The paper is adapted to be inserted between the finger and roller which serves to hold it against inadvertent movement on the printing bed, and means are provided for raising the finger 27, to permit of insertion and removal of the paper, comprising an apertured leaf 29 with which engages a finger 30 on a spindle 31, the latter 95 being rocked to raise the finger 27 by means of an arm 32 connected to the spindle and to a plunger 33 extending without the casing, as disclosed in the patent referred to above, so that a more detailed description of these 100 parts will not be required.

Fixed at 34 on the casing 2 is a guard plate 35 to protect the work from being smeared by the inked type; the guard being provided above the platen with a slot 36 105 slightly wider than the surface of the platen, so that as the latter rises it presses the work slightly through the slot into position for engagement with the type.

The embossing detecting device for preventing the printing in the machine of paper previously embossed or disrupted by an impression comprises a spring plate 37 provided with depending points 38, the plate being supported by the guard plate 35 and 115 located in the slot 36 in the latter so that when the paper is raised by the platen the points 38 bear resiliently upon the upper surface of the paper just before the latter reaches the printing couple, as illustrated 120 in Fig. 5.

Fixed on the upper side of the platen arm 19 is a bracket 39 pivotally supporting an upwardly extending needle 40. This needle is mounted on a spindle 41 carried in the 125 bracket 39 and the extended end of the spindle carries a leaf spring 42 engaging a lug 42a on the needle, thus holding the latter, yielding, in substantially vertical position, as shown in Fig. 5, where the paper is repre- 130

sented by the numeral 43. In the normal positions of the parts, the platen and the needle 40 being in lowered position, and the part 38 somewhat elevated above the printing bed, the work may be freely inserted in the machine between the members of the printing couple. At the beginning of the printing operation the platen and needle 40 rise, carrying the work into contact with the detecting part 38 above the work, needle 40 being brought by the feeding movement of the work to the inclined position shown in Fig. 5, so needle 40 engages the work yieldingly from below and the part 38 from above. New work with unembossed surface feeds freely between detecting parts 38 and 40, but if the work has been previously embossed or disrupted, as by a protective impression of the character described, the pressure of needle 40 and of the part 38 on the work, causes them to hook the disrupted fibers and thus engage and mutilate or tear the paper in that portion which has previously been impressed, so that the feeding movement of the paper is obstructed or else the paper is effectually destroyed. The points are placed so close to the printing couple that it is difficult to tamper with them in a manner to prevent their operation.

30 A means is provided to coöperate with the printing couple to feed the work more positively through the machine comprising a small gear 44 fixed to the platen spindle and meshing with a similar gear 45 fixed on a spindle 46 journaled in the arms of a substantially U-shaped swinging frame 47 which is pivotally supported at one end on the platen spindle 18 and resiliently supported at its other end by a spring 48 fixed on the base 1. The gear 45 meshes with a gear 49 fixed on a spindle 50 which is journaled in the frame 47 and provided with a pair of paper feeding wheels 51. The platen arm 19 has fixed thereon a finger 48 engaging the upper side of spindle 46 of the frame 47. Therefore when the platen is depressed, spindles 18 and 46 of the frame 47 are both depressed and carry downwardly with them the frame, 47 against the tension 50 of spring 48. When the platen is raised, its spindle 18 and the spring 48 raise frame 47 and carry wheels 51 against the guard plate 35 thus pressing the paper between the wheels and the guard. As the platen is rotated by the engagement therewith of the rolling type forms, the gearing described serves to rotate the wheels 51 and thus assist in feeding the paper through the machine.

60 The operation of the machine, briefly, is as follows: The plunger 33 having been depressed to raise the finger 27, the check is inserted in the slot 3 at the right side of the machine so that the left end of the check 65 lies on the printing bed above the platen wheel. The handle 8 is then moved to select the first type form to be impressed, the plunger 33 having been released after the location of the paper in the machine, and the crank 13 is then rotated to print and feed the check through the machine. As already described, if the line provided for receiving the inscription of the amount on the check has been previously marked, with an impression, the points of the mutilating device immediately sink into the paper as the disrupted portion passes toward the platen and obstruct the feeding of the check or else effectually mutilate it in the manner described. The device thus makes it impossible to alter the inscription of a check, by superposing on any portion of the inscription a second impression to make the check call for a larger amount than was originally intended to be conveyed.

Having thus described our invention, what we claim as new, and desire to secure by Letters Patent is:—

1. The combination with a marking apparatus including work embossing parts; of an embossing detecting device including a work engaging part below the work for detecting and tearing a previously embossed portion thereof.
2. The combination with a printing machine adapted to disrupt the paper during the printing operation; of a device comprising a pointed member for engaging the paper from above; and also a pointed member for engaging the paper from below, said points operating to tear a previously disrupted portion of the paper to prevent a second printing impression thereon.
3. The combination with a printing machine provided with a type form and platen having a relative movement to impress the paper, and adapted to disrupt the latter by said impression; of a device comprising a part adapted to be brought into contact with the paper by said relative movement of the movable parts, and to engage and tear a portion of the paper disrupted by a previous impression to prevent a second impression on the paper.
4. The combination with a printing machine provided with a type form, and a platen movable into printing coöperation with said form, said form and platen being adapted to disrupt the paper during the printing operation; of a device having a part adapted to be moved into contact with said paper from below by the movement of said platen, and to engage and tear a portion of the paper disrupted by a previous impression to prevent a second impression on the paper.
5. The combination with a printing machine provided with a type form and platen having a relative movement to impress the paper, and adapted to disrupt the latter by

said impression; of a device comprising a plurality of parts, one of which is movable by said relative movement of the type form and platen, said parts being adapted to contact with the paper from opposite sides and to engage and tear a portion of the paper disrupted by a previous impression to prevent a second impression on the paper.

6. The combination with a printing machine comprising a printing couple the members of which are relatively movable to print and disrupt the paper, and means for feeding the work between the members of the printing couple; of a pointed part

movable to engage the paper from below 15 by said relative movement of the members of said printing couple, and adapted to yield to permit said paper to be fed but to bear against said paper during the feeding movement in order to engage and tear a portion 20 of the paper disrupted by a previous impression of the machine.
